FIG. 1.

FIG. 2.

Inventor
GEORGE CLAUSING,
By Paulmin Paulmin

Attorneys

Patented Jan. 12, 1926.

1,568,962

UNITED STATES PATENT OFFICE.

GEORGE CLAUSING, OF PORTSMOUTH, OHIO, ASSIGNOR TO THE VULCAN LAST COMPANY, OF PORTSMOUTH, OHIO, A CORPORATION OF OHIO.

LAST.

Original application filed March 26, 1924, Serial No. 701,986. Divided and this application filed September 29, 1924. Serial No. 740,536.

To all whom it may concern:

Be it known that I, GEORGE CLAUSING, a citizen of the United States, residing at Portsmouth, in the county of Scioto and 5 State of Ohio, have invented certain new and useful Improvements in Lasts, of which the following is a specification, reference being had therein to the accompanying drawing.

10 My invention relates to lasts, and the present application is a division of my application filed March 26, 1924, Serial No. 701,986.

15 It is the object of my invention to provide a last having spring links so that the last parts will remain in their expanded or collapsed condition and resist movement from one position to the other.

20 It is a further object of my invention to provide a dual link construction so arranged that the resiliency and resistance of the link parts that must be overcome will be uniform, no matter whether the parts are being moved from expanded to collapsed position 25 or vice-versa.

It is a still further object of my invention to provide resilient links which will readily return to their original form after the last parts pass by their dead center, as the 30 parts are so arranged that a line drawn between the points of attachment of the links to the last parts will pass over the pivotal center about which the last parts move.

35 Referring to the drawings:

Figure 1 is a section through the last in its expanded position.

Figure 2 is a similar view of the last in its collapsed position.

40 Referring to the drawings in detail:

1 designates the toe part and 2 the heel part of the last. These two parts are provided with a knuckle or ball and socket joint, of which 3 is the ball and 4 is the 45 socket. The center of the ball is designated 5 and it is about that center that the parts 1 and 2 move. The upper portions of these last parts are cut away as at 6 so that the last parts can collapse. The faces 7 limit 50 the movement of the last parts in their expanded position.

The pins 8 and 9 in the toe and heel parts respectively are located transversely in such parts and they carry links 10 in the form of 55 resilient hooks which have enlarged eyes 11

at the point of their mounting upon the pins 8 and 9. It will be noted that the major portion of such hooks is above the line joining their centers.

When the last parts pass over dead center 60 or this line joining the centers of the pins 8 and 9 passes over the point 5, the resilient links 10 flex sufficiently to permit of this passage over dead center. Additional resiliency may be found in the last parts themselves if they are made of such material as 65 wood.

By having two links in reverse positions it will be apparent that the resistance will be equalized and be made uniform no matter 70 in which direction the parts are being moved.

It will also be observed that the last parts are cut away as at 12 and 13, so that the movement of the links and the links themselves 75 may be accommodated within the last parts.

The pivotal point indicated on the drawings is only approximate, but it is accurate sufficiently to illustrate the principle of construction as the drawings are not drawn to scale. The fundamental idea is to have the line drawn between the centers of the points of attachment pass over the dead center, which in a sense is the equivalent of the 80 pivotal point.

It will be understood that I desire to comprehend within my invention various modifications which may be found necessary in adapting it to the various requirements 85 of the art.

Having thus fully described my invention, what I claim as new and desire to secure by Letters Patent of the United States, is:

1. In a last, a toe part and a heel part pivoted on one another about a given center forming a joint therebetween so that the parts can rock on one another about said common center, a link connecting said parts 100 mounted on pins in said parts so arranged that it has no lateral movement on the pins and so formed that it proceeds from one pin upwardly to a point above the other pin and then downwardly to form an angular 105 spring-like hook which is adapted to flex when the last parts pass over the common center of movement and to hold the parts in their expanded or collapsed position when they are so moved.

95

100

105

110

2. In a last, a toe part, a heel part, a joint therebetween so that the parts can rock on one another about a common center, a link connecting said parts bent to form a 5 spring-like hook which is adapted to flex when the last parts pass over the common center and to hold the parts in their expanded or collapsed position, and a second hook-like link having the hook oppositely disposed from the first mentioned hook, the major portion of said hooks being located to one side of a line drawn between their centers of attachment to the last parts and forming an S-shaped construction.

10 3. In a last, a toe part, a heel part, a joint therebetween so that the parts can rock on one another about a common center, a link

connecting said parts bent to form a spring-like hook which is adapted to flex when the last parts pass over the common center and to hold the parts in their expanded or collapsed position, and a second hook-like link having the hook oppositely disposed from the first mentioned hook, the major portion of said hooks being located to one side of a line drawn between their centers of attachment to the last parts and forming an S-shaped construction. 15

20 In testimony whereof, I affix my signature.

25 GEORGE CLAUSING.
